DESIGN FOR A SHOE OR SIMILAR ARTICLE

Linus W. Bagg, Montclair, N. J.

Application February 27, 1939, Serial No. 83,232

Term of patent 14 years

To all whom it may concern:

Be it known that I, Linus W. Bagg, a citizen of the United States, residing at Montclair, in the county of Essex and State of New Jersey, have invented a new, original, and ornamental Design for a Shoe or Similar Article, of which the following is a specification, reference being had to the accompanying drawing, forming part thereof.

I claim:

The ornamental design for a shoe or similar article, as shown.

LINUS W. BAGG.
